UNITED STATES PATENT OFFICE.

JAMES J. LANAHAN, OF BUFFALO, NEW YORK.

SIGNAL FOR VEHICLES.

1,357,064.

Specification of Letters Patent. Patented Oct. 26, 1920.

Application filed November 16, 1917. Serial No. 202,265.

To all whom it may concern:

Be it known that I, JAMES J. LANAHAN, a citizen of the United States, residing at Buffalo, in the county of Erie and State of New York, have invented new and useful Improvements in Signals for Vehicles, of which the following is a specification.

This invention relates to a signal for automobiles or other vehicles for indicating the direction which the vehicle is about to take or whether the same is about to stop, and thereby avoid traffic accidents.

It is the object of this invention to provide a signal of this character which is simple and compact in construction, neat in appearance, efficient and reliable in operation and low in cost.

In the accompanying drawings:

Figure 1 is an elevation, on a reduced scale, of my improved signal showing the same applied to the wind shield of an automobile and the movable parts being shifted into their operative position. Fig. 2 is a vertical longitudinal section of this signal, on an enlarged scale. Fig. 3 is a horizontal section taken on the correspondingly numbered line in Fig. 2. Fig. 4 is a vertical transverse section, on an enlarged scale, taken on line 4—4, Fig. 2. Fig. 5 is a fragmentary, vertical, longitudinal section taken on line 5—5, Fig. 4. Fig. 6 is a detached inside elevation of the disk of the electric switch which controls the circuit of the signal lamp forming part of this invention.

Similar characters of reference indicate corresponding parts throughout the several views.

In its general organization this signal comprises a support which is preferably constructed in the form of a casing and a signal device which is movably mounted on this support so as to be capable of being projected laterally from the casing into its operative position for giving a signal, or retracted into its inoperative position within the casing for terminating the signal. The casing 1 which forms the support in the present instance is preferably constructed of sheet metal and has an opening in its outer side through which the signal device is adapted to move into and out of the casing. This casing may be mounted on any suitable or convenient part of the vehicle, for instance, on the frame 2 of the wind shield of an automobile, for which purpose a clamping device is provided which comprises two

clamping jaws 3, 4, engaging with opposite sides of an upright bar of the wind shield frame and a clamping bolt 5 which passes horizontally and transversely through these clamping jaws, the inner part of the casing and a spacing sleeve 6 arranged within the casing, as best shown in Figs. 2 and 3. The opening on the outer side of the casing is covered and uncovered by means of a lid or door 7 which is preferably pivotally connected at its lower end by a hinge 8 with the lower part of the casing so that this lid can either swing into its upright closed position or downwardly into a horizontal open position. On the inner side of this lid is mounted the signal device which is so constructed that it displays a signal during the day time and also during the night time. In its preferred form the signal device comprises a semaphore of sheet metal having a longitudinal bar or plate 9 arranged parallel to the lid, a lug 10 arranged at the inner end of the bar and secured to the lid adjacent to the pivotal connection of the same with the casing and a ring 11 arranged at the outer end of the semaphore bar and secured to the outer or upper part of the lid. This lid, together with the signal device mounted thereon, may be moved inwardly and outwardly into its inoperative and operative position, by any suitable means, for instance, by a shifting rod 12 arranged horizontally within the lower part of the casing and passing through an opening 13 in the rear or inner wall thereof and pivotally connected at its outer end by means of a screw 14 with the semaphore lug while its inner end is provided with a finger piece or handle 15 whereby this rod may be actuated manually.

16 represents an electric light bulb mounted on the semaphore so that its filament is arranged in line with the opening within the ring 11 and when illuminated serves as a night signal on opposite sides of the semaphore. Current may be supplied by wires 17, 18 to this lamp from any suitable source, for instance, the generator or storage battery 19 now commonly employed in connection with the ignition and illuminating systems of automobiles. A switch mechanism is provided whereby this lamp will be automatically lighted when the signal device is moved outwardly into its operative position and extinguished when the same is returned to its normal inoperative position. In the preferred form of this switch mechanism

the same is combined with a stop device whereby the outward movement of the signal device into the operative position is limited, this stop device as shown in the drawings, being preferably constructed as follows:

20, 21 represent two switch supporting disks which are constructed of vulcanite or similar material, the disk 20 being relatively fixed and secured to the inner part of the semaphore by means of a rivet 22, as shown in Fig. 4, and the other disk 21 being rotatable concentrically relative to the fixed disk and pivotally connected therewith and 10 the semaphore by means of a pivot-bolt having a hollow shank 23 which passes axially through both switch supporting disks and the semaphore and engages its head 24 with the outer side of the movable switch disk 20 while its nut 25 engages with the outer side 15 of the semaphore, as best shown in Fig. 4. On the opposing sides of the switch disks are arranged the contact members which are adapted to form parts of the circuit of 20 the electric lamp and to open and close this circuit upon turning these switch disks one relatively to the other. In the preferred form of this switch the fixed disk 20 is provided with two metallic contacts 26, 27, to 25 which the circuit wires are connected and the relatively rotatable disk 21 is provided with a metal bridge contact 28 which is adapted to cooperate with the fixed contacts 26, 27, of the other disk. The arrangement and construction of the contacts of 30 these two switch disks is preferably such that the bridging contact 28 of the disk 21 engages with only one of the contacts of the fixed switch disk when the lid, semaphore 35 and lamp are in their retracted or inoperative position, thereby breaking the circuit of the lamp and extinguishing the same at 40 this time, but upon moving the lid, semaphore and lamp outwardly into a laterally-projecting position relative to the casing for giving a signal, the bridging contact 28 of the movable switch disk engages with both 45 fixed contacts 26, 27, immediately after the initial opening movement of the lid, semaphore and lamp is effected, until these members reach their outermost position, thereby causing the lamp to be not only illuminated while in its farthermost or projected position but also causing the same to produce a 50 sweeping light as it moves outwardly from the casing and back again, whereby a more effective signal is given than would be the case if the lamp were simply lighted and extinguished while in its outmost position. 55 The turning movement of the rotatable switch disk is effected by means which also form part of the stop device which limits the outward movement of the semaphore, lid and lamp, and as best shown in Figs. 2, 60 3 and 4, the switch actuating and stop 65

means preferably comprise a stop lug 29 arranged within the casing and secured to the rear wall thereof, a stop rod 30 slidable through an opening 31 in said lug and provided at its rear end with a stop or head 32 70 which is adapted to engage with the rear side of said lug, a pivot pin or wrist 33 projecting laterally from the front end of the stop rod through the hollow shank 23 of the bolt from the head-end thereof, a nut 75 34 applied to this pivot pin and engaging with the nut end of the bolt shank 23, and a staple-shaped fastening 35 for connecting the stop rod with the outer side of the movable switch disk. 80

Upon shifting the lid and the parts mounted thereon outwardly, the stop rod slides outwardly in the lug 29 until the stop head 32 at its inner end engages with this lug at which time the outward movement of the lid is arrested and in the preferred organization is so determined that the lid, semaphore and lamp project laterally at this time from the casing, as shown by full lines in Figs. 1, 2 and 3. Upon swinging the lid 90 and the parts mounted thereon upwardly and inwardly into their retracted position so that the signal devices are inclosed within the casing, the stop rod slides inwardly and upwardly through the stop lug into the 95 position indicated by dotted lines in Fig. 2. During such sliding movement of the stop rod through the stop lug, the front end of the same and the movable switch disk 21 connected therewith turn relatively to the 100 fixed switch disk 20 so that this switch operates to complete the circuit of the lamp and give a light signal upon moving the lid, semaphore and lamp outwardly and inwardly and to extinguish the lamp during 105 the last part of the retracting movement of the lid and associated parts.

In order to cut off the source of electricity from the lamp during day time when the light is not required, an auxiliary hand switch 36 is provided in the circuit which may be of any suitable construction.

As a whole, this signal comprises very few parts which can be easily assembled, the structure is very compact and presents a 115 neat appearance and the same contains no delicate parts which are likely to get out of order, thereby rendering the same particularly suitable for use as a direction signal for automobiles which will serve to indicate 120 the intention of the driver during the day time or during the night time as to whether the particular driver intends to stop or turn toward the right or toward the left, whereby the safety of pedestrians and the passengers 125 is increased.

I claim as my invention:

1. A vehicle signal comprising a casing, a semaphore pivotally mounted on said casing and movable into and out of the same, a 130

stop device for limiting the opening movement of said semaphore comprising a stop lug arranged on the inner side of said casing and a stop rod slideable on said lug and provided at its inner end with a stop adapted to engage with the back of said lug while its outer end is pivotally connected with said semaphore on one side of the pivotal connection between the latter and the casing, an electric lamp mounted on said semaphore, and an electric switch having contacts arranged in the circuit of said lamp and adapted to be engaged and disengaged by the relative rotary movement of said semaphore and stop rod.

2. A vehicle signal comprising a casing, a semaphore pivotally mounted on said casing and movable into and out of the same, an electric lamp mounted on said semaphore, an electric switch mounted on said semaphore and comprising two insulating disks, one of which is fixed on the semaphore and the other rotatable relatively to said fixed disk, coöperating contacts arranged in the circuit of said lamp and mounted respectively on said disks, and means for turning said disks relatively to one another upon

moving said semaphore into and out of its operative position.

3. A vehicle signal comprising a casing, a semaphore pivotally mounted on said casing and movable into and out of the same, an electric lamp mounted on said semaphore, an electric switch mounted on said semaphore and comprising two insulating disks one of which is fixed on the semaphore and the other rotatable relatively to said fixed disk, coöperating contacts arranged in the circuit of said lamp and mounted respectively on said disks, means for pivotally connecting said disks comprising a hollow pivot bolt passing axially through said disks and bearing with its head against the pivoted disk and with its nut against the semaphore, and means for turning said movable disk and limiting the outward movement of said semaphore comprising a stop lug arranged on said casing, and a stop rod slideable in said stop lug and provided at its inner end with a stop engaging with said lug and at its outer end with a laterally projecting pivot wrist which is arranged in said hollow bolt and connected with said rotatable disk.

JAMES J. LANAHAN.
